UNITED STATES PATENT OFFICE.

ALEXANDER W. WOODLEY, OF BLALOCK, ALABAMA.

COMBINATION CLINKER-BAR AND FIRE-RAKE.

1,036,401.

Specification of Letters Patent. Patented Aug. 20, 1912.

Application filed February 26, 1912. Serial No. 680,038.

To all whom it may concern:

Be it known that I, ALEXANDER W. WOODLEY, a citizen of the United States, residing at Blalock, in the county of Dallas and State 5 of Alabama, have invented a new and useful Combination Clinker-Bar and Fire-Rake, of which the following is a specification.

My invention relates to improvements in combination clinker bars and fire rakes, and 10 has for its object to provide a readily adjustable tool, which, while primarily designed for use in connection with furnaces, can with equally obvious facility be employed for other purposes.

15 Other objects and advantages of my invention will appear in the course of the following specification.

In the accompanying drawings: Figure 1 is a side elevation of my improved clinker 20 bar and fire rake. Fig. 2 is a front elevation of the same, partly in section. Fig. 3 is a longitudinal sectional view. Fig. 4 is a side elevation, partly in section, with the movable parts shown in different positions than in 25 the other figures.

Referring to the drawings, which illustrate the preferred embodiment of my invention, 5 designates a shaft or rod provided at one end with a slot 6 in which is pivotally 30 mounted at 6^a the tang 7 of a tool head 8. As shown, the tang 7 is preferably a centrally-arranged continuation in line with the tool head. Extending from the tool head and positioned one on each side of the tang 35 7 are prongs or fingers 9, which extend beyond the end of the tang and at their ends are beveled to a point. The main portion of the tool head extends beyond the shaft and is flat on one face and beveled on the other 40 face. The tool head gradually widens from the prongs outwardly, and the outer edge is straight, as shown in Fig. 2.

Mounted on the shaft 5 is a tubular sleeve 10 provided with a longitudinal slot 11 near 45 one end. Secured to the shaft 5 is a projection or pin 12, which projects into the slot 11. A short, transverse notch 13 opens into the longitudinal slot 11 near its outer end, and toward its other end, and on the oppo- 50 site side thereof, another short transverse notch 14 opens into the slot 11. The purpose of the notches 13 and 14 is to coöperate with the other parts in the manner herein- after explained to lock the tool head 8 together 55 with its tang 7 and prongs 9 in the positions shown in the drawings.

As illustrated in Fig. 2, when the tool head 8, its tang 7 and prongs 9 are arranged in line with the shaft 5, the tang lies in the slot 6 and the prongs 9 extend one on each side of the sleeve 10. The end of the sleeve incloses the end of the shaft 5 together with its slot 6 and the tang 7, and by drawing upon the shaft, the sleeve is forced up to contact with the inner side of the tool head, and then 60 by rotating the shaft the pin 12 is positioned in the outer transverse notch 13 to lock the sleeve and shaft against relative movement, and thus firmly hold the parts in 65 position.

Fig. 4 shows the tool head 8 together with its prongs 9 arranged at right angles to the shaft 5 and sleeve 10. This is accomplished by turning the shaft slightly to release the pin from the notch 13, and then sliding the 70 shaft outwardly to uncover the tang 7 positioned longitudinally in the slot 6, when the tool head and prongs can be swung to the position shown in Fig. 4. The notch 14 in the sleeve 12 is then brought opposite the 75 pin 12, when the shaft can be turned sufficiently to place the pin in engagement with the notch to lock the sleeve in position. In this position the end of the sleeve will abut 80 against the side of the tang at points on each 85 side of its pivot point 6^a and thus hold the tang, tool head and prongs firmly in position.

While in the foregoing description it has been stated that the shaft is moved with 90 respect to the sleeve to effect the various adjustments of the tool head 8, its tang 7 and the prongs 9, it is apparent that the adjustments could be made by moving the sleeve with respect to the shaft. The free end of 95 the shaft 5 is flattened and rounded at 15 and provided with an aperture 16 by which the tool can be suspended when desired.

In the position shown in Figs. 1, 2 and 3, the blade portion of the tool is only operative and the device is employed as a clinker 100 bar. When in the position shown in Fig. 4, the prongs and the blade portion are set for use as a fire rake.

I do not limit myself to the precise form 105 of locking means shown and described in the foregoing specification, but reserve the right to substitute therefor any other suitable locking means.

What is claimed is:-

1. In a combination tool, a shaft provided with a slot at one end, in combination with

a tool head, having a tang, said tang being pivotally mounted in said slot, a sleeve mounted on said shaft to cover and hold said tang in position when said tang lies longitudinally within said slot, projecting prongs carried by said tool head and extending in the same direction as and beyond said tang, said prongs being normally positioned along the sides of said sleeve, and means for securing said sleeve and said shaft against relative movement to hold said tool head and prongs in a position at right angles to said shaft whereby said prongs will be in an operative position.

15 2. In a combination tool, the combination with a shaft provided with a slot at one end, a tool head having a tang, said tang being pivotally mounted in said slot to permit said

tool head to be swung in line with said shaft or at an angle thereto, a slotted sleeve loosely mounted on said shaft, said sleeve being adapted to cover said tang when said tang is arranged in line with said shaft, a pin secured to said shaft and working in the slot of said sleeve to limit the relative movement of said sleeve and shaft, and notches provided in the slot of said sleeve to engage said pin and hold said sleeve and shaft in adjusted positions.

In testimony, that I claim the foregoing as my own, I have hereto affixed my signature in the presence of two witnesses.

ALEX. W. WOODLEY.
